(No Model.)

W. G. & J. H. CUMMINS.

HORSE DETACHER.

No. 309,694.

Patented Dec. 23, 1884.

UNITED STATES PATENT OFFICE.

WILLIAM G. CUMMINS AND JUBAL H. CUMMINS, OF McMINTVILLE, TENN.

HORSE-DETACHER.

SPECIFICATION forming part of Letters Patent No. 309,694, dated December 23, 1884.

Application filed May 14, 1884. (No model.)

To all whom it may concern:

Be it known that we, WILLIAM G. CUMMINS and JUBAL H. CUMMINS, of McMinnville, in the county of Warren and State of Tennessee, have invented certain new and useful Improvements in Trace-Detachers; and we do hereby declare the following to be a full, clear, and exact description of the invention, such as will enable others skilled in the art to which it applies to make and use the same.

Our invention relates to an improvement in devices for detaching horses, and more particularly to an improvement upon a device for this purpose, for which Letters Patent No. 267,331 were granted to William G. Cummins, November 14, 1882, the object of the same being to provide a trace-detacher which may be adjusted to suit single-trees of different size; a further object being to provide an improved construction of the slide-bar, whereby the same may be applied to either end of the single-tree, have a direct longitudinal motion, and have a concave bearing on the single-tree, a further object being to provide an improved catch for holding the latch-lever against accidental displacement.

With these ends in view our invention consists in certain features of construction and combinations of parts, as will be hereinafter described, and pointed out in the claims.

In the accompanying drawings, Figure 1 is a view in perspective of one end of a single-tree provided with our improvement, the parts being in a locked position. Fig. 2 is a similar view showing the parts in the detaching position, and Fig. 3 is a detached view of the slide-bar.

A represents one end of a single-tree provided with a trace-pin, *a*, centrally located in the end of the single-tree.

A slide-bar, *B*, provided with a concave under surface adapted to closely fit a portion of the cylindrical surface of the single-tree, is bent downward at the outer end to form a guard, *b*, which guard is adapted to rest in contact with the end of the pin *a* and hold the trace on the pin. The slide-bar *B* is preferably widened at its inner end, as shown, and provided with the elongated longitudinal closed slot *C*, and with the two transverse closed slots

c, similarly situated on opposite sides of the slot *C*. The purpose of the slots *C* and *c* will appear farther on. The bar *B* is further provided with a vertical perforation, *D*, just outside of the end of the single-tree proper, in which the stem of a ring or eye, *d*, which serves as a trace-detacher, is adapted to be received and firmly held, either by a screw-thread or by being driven snugly. The eye *d* is adapted to loosely embrace the trace-pin *a*, and as the bar slides outward slides the trace off the end of the pin, and can be adjusted lengthwise to enable it to accommodate itself to single trees of different diameters.

A latch-bar, *E*, shaped to conform to the upper surface of the slide-bar *B*, is provided with a perforation, *e*, situated in a position directly over the outer end of the slot *C*, when the bar *E* is in position on the bar *B*, through which perforation and slot a screw or bolt, *F*, passes into the single-tree, and thereby locks the bar *E* to the bar *B*, and both to the single-tree. The bar *E* is further provided with a depending stud, *f*, which engages one of the transverse slots *e* in the bar *B*, and with a ring or other suitable device for attaching a cord, wire, or chain at or near its outer end. The latch-bar *E* is also provided with an open V-shaped recess, *G*, on the under side of its outer end, which engages a similar-shaped projection, *g*, on the upper surface of the bar *B*, and locks the latch against accidental displacement. The spring of the bar *E*, when constructed of brass, steel, or cast malleable iron, is sufficient to allow the bar *E* to move over the projection *g* and hold the bar in contact therewith; but, if found desirable to use metal which has little or no spring, a spring-washer, *H*, may be introduced between the head of the screw or bolt *F* and the bar *E*.

We find it convenient to have the bar *B* shouldered at a point near the end of the single-tree proper, rising about the thickness of the latch-bar *E*, and thus forming, when the latch-bar is in position, an even upper surface from the inner to the outer end of the bar *B*.

A cord attached to the outer end of the latch-bar and leading within reach of the driver brings the device under his immediate control, as a backward pull on said cord will

swing the latch-bar E rearwardly, and by the engagement of the stud f in the slot e will force the bar B outwardly the length of the slot C, which corresponds to the length of the trace-pin a, and by means of the trace-detacher d slips the trace from the pin a and sets the horse free. A similar bar on the opposite end of the single-tree, having the stud in the latch-bar engaging the opposite slot c, will produce the same effect upon the tree at that end when the latch-bar is swung rearwardly, and by any convenient connection of the operating-cords the two may be moved simultaneously.

15 It is evident that slight changes may be made in the form and construction of the several parts without departing from the spirit and scope of our invention; hence we do not wish to limit ourselves strictly to the construction herein set forth; but,

Having fully described our invention, what we claim as new, and desire to secure by Letters Patent, is—

1. The combination, with a single-tree and its trace-pin, of a slide-bar provided with a trace-retaining and an adjustable trace-shipping device, and a latch bar or lever pivoted to the single-tree through the said slide-bar, and adapted to slide the bar longitudinally, substantially as set forth.

2. The combination, with a single-tree provided with a trace-pin, and a slide-bar secured on the single-tree and provided with a trace-retaining device, of a trace-detacher adjustably secured to the retaining-bar, and a lever for locking and moving the bar, substantially as set forth.

3. The combination, with a trace-retaining and trace-shipping sliding bar secured to the end of a single-tree and provided with a lon-

itudinal and a transverse slot, of a latch-lever pivoted to the single-tree through said longitudinal slot and provided with a stud which engages said transverse slot, whereby the lateral swing of the latch-lever moves the 45 sliding bar longitudinally, substantially as set forth.

4. The combination, with a single-tree and its pin, of a trace-retaining and trace-shipping sliding bar provided with a longitudinal and two transverse slots, whereby it is adapted to occupy either end of the single-tree and be operated thereon, substantially as set forth.

5. The combination, with a single-tree and its pin, of a trace-retaining and trace-shipping 55 sliding bar provided with a V-shaped cam on its upper surface, and with longitudinal and transverse slots, and a latch-lever pivoted to the single-tree through the longitudinal slot, said latch-lever having a V-shaped recess in its outer end and a stud in engagement with said transverse slot, whereby it locks and moves the sliding bar, substantially as set forth.

6. The combination, with a single-tree and a trace-pin secured in its end, of a trace-shipping and trace-retaining sliding bar, a latch-lever pivoted to the single-tree through the sliding bar, a spring-washer between the latch-lever and pivot-bolt or screw-head, and operating-ring secured to the outer end of the latch-lever, substantially as set forth.

In testimony whereof we have signed this specification in the presence of two subscribing witnesses.

WM. G. CUMMINS.
JUBAL H. CUMMINS.
